CARBURETER.

1,180,152.

Specification of Letters Patent.

Patented Apr. 18, 1916.

Application filed July 14, 1914. Serial No. 850,900.

To all whom it may concern:

Be it known that I, WRIGHT E. HOWES, a citizen of the United States, residing in the city and county of San Francisco and State of California, have invented new and useful Improvements in Carbureters, of which the following is a specification.

This invention relates to carbureters.

One of the objects of the present invention is to provide a simple, substantial, easily adjusted carbureter, which is especially constructed for handling low gravity fuel oils, such as distillates and the like; and to provide a multiple jet spray nozzle, together with a novel form of air valve, which is adapted to throw the spray over the largest amount of area possible, thereby assisting vaporization.

Another object of the invention is to provide means for heating the gaseous mixture which passes through the carbureting chamber to further assist vaporization.

The invention consists of the parts and the construction and combination of parts as hereinafter more fully described and claimed, having reference to the accompanying drawings, in which—

Figure 1 is a cross section on line 1—1, Fig. 2. Fig. 2 is a longitudinal section on line 2—2, Fig. 1. Fig. 3 is an enlarged plan view of the needle valve adjusting collar. Fig. 4 is a side elevation of same. Fig. 5 is an end elevation of the carbureter. Fig. 6 is a cross section on the line 6—6, Fig. 1. Fig. 7 is a horizontal section on line 7—7, Fig. 1. Fig. 8 is a plan view of the lower auxiliary air valve. Fig. 9 is a plan view of the upper auxiliary air valve. Fig. 10 is a plan view, showing the relative position of the inlet ports in the upper and lower air valves.

A indicates the mixing chamber of the carbureter, in which is mounted a ribbed pipe 2, through which the unobstructed exhaust from the engine (not here shown) is directed.

3 is the main intake end of the carbureter which leads to the mixing chamber, and 4 the outlet from same.

50 Secured on one side of the carbureter, near the inlet opening 3, is a float chamber 5 with which the fuel supply pipe is connected, as at 6, and mounted in said chamber is a needle valve 7 and a float 8, which 55 float 8 is connected with the needle valve

by means of the pivoted arms and links 9. The lower end of the needle valve is threaded and extends through a collar 10 through which connection is made with the float; while the upper end of the 60 needle valve extends through the cover of the float chamber and is provided with a nut or finger grip 11 by which the needle valve may be turned and adjusted with relation to the seat 12. The fuel level or supply admitted to the float chamber may thus be regulated from the exterior of the carbureter without disturbing any connections or removing any parts.

13 is a connection formed on one side of the float chamber which extends into the intake end 3 of the carbureter, and formed on the end of said extension is an upturned extension 14, on the upper end of which is formed a horizontally positioned, cylindrical-shaped spray nozzle 15. The upper face of this spray nozzle is provided with a slot 16 which extends the entire length of the same. Mounted in the interior of the cylinder and controlled by a crank arm 17 is 70 a valve 18, on the lower side of which is formed a continuous passage 19, and on the upper side of which is formed a plurality of discharge openings 20. The turning of the valve, by means of the crank arm 17, 75 will bring the openings 20 into and out of register with the slot 16, thus controlling the amount of fuel delivered through same.

80 Mounted on each side of the horizontally positioned spray nozzle is a wing valve 21, the valves being mounted upon rods 22 which extend through the ends of the carbureter casing and carry crank arms 23 on their outer ends which extend into a slotted bar 24. The slotted bar 24 is carried by an adjustable screw 25 mounted in a lug 26 formed on the exterior of the carbureter casing. The lifting of the slotted bar 24, by means of the screw 25, will transmit movement, through the crank arms 23, and will 85 consequently move the valves 21 in unison up or down, with relation to the slot in the spray nozzle. The position of the wing valves is adjusted so that the air velocity at the nozzle is sufficiently great, at the slowest engine speed, to overcome the initial lift necessary to bring the fuel to the nozzle level and draw it into the carbureting chamber.

100 In practice, the fuel is first admitted,

through the connection 6, to the float chamber 5, where the level and quantity admitted are controlled by the float 8 and needle valve 7. The fuel then passes through a passage 27 and is from there permitted to enter into the continuous valve passage 19, from where it is finally discharged through the openings 20 and slot 16 into the carbureting chamber; the position or register of the 10 openings 20 controlling the volume of discharge and evenly dividing the spray which is picked up by the incoming air and projected against the ribbed exterior surface of the exhaust pipe 2. This being hot will immediately vaporize the fuel and cause it to thoroughly mix with the air entering between the wing valves 21. A perfectly vaporized, homogeneous mixture is thus produced which increases in temperature as it 20 passes around the exterior ribbed surface of pipe 2.

A wire screen 28 covers the lower exterior surface of the exhaust pipe and is provided for the purpose of breaking up the small 25 globules discharging from the spray nozzle before they contact with the heated surface of the exhaust pipe. It also tends to mix the air and spray and will thus, to a certain degree, promote vaporization.

30 A novel form of auxiliary air valve has been provided in the present device which is adapted to operate in conjunction with the throttle valve 29. The throttle valve is in this instance secured upon a rod 30 which is 35 turnably mounted in a nipple 31 secured in the outlet end of the mixing chamber. Secured exterior of the nipple is a collar 32, having an upwardly turned flange 33 formed thereon, and turnably mounted, exterior of the nipple, and adapted to seat upon the flange 33, is an auxiliary air valve 34. One side of said valve is provided with gear teeth 35 which are adapted to intermesh with teeth 36 formed on the segment 37 carried by the rod 30. Any movement of the throttle valve is thus transmitted through rod 30 and gear segment 37 to turn the valve 34. They are thus operated or moved in unison and the action will be as follows: 40 The valve 34 is provided with two air inlet openings 34^a and 34^b and the air admitted through these openings is permitted to enter the annular space formed between the annular flange 33 and the exterior wall of the 45 nipple. The air is then permitted to pass through a plurality of radially disposed openings 38, formed in the nipple, and will thus enter directly into the vapor duct and mix with the gases from the carbureting 50 chamber.

55 Mounted above the valve 34 is a second valve 39 and formed in said valve is a pair of air inlet openings 39^a and 39^b of a shape similar to those shown in valve 34, but 60 placed in an opposite position to same, and

mounted above said valve is a collar 40, upon which is formed a downwardly turned, flange 41. An annular passage is thus formed between the collar 40 and the valve 39 to which air is admitted through a series 70 of perforations 42. The collar 40 does not only serve the function of an air inlet cover for the valves 34 and 39 but also acts as a disk or washer by which the valves are clamped and held in position upon the annular flange 33. 75

In operation, air will enter through the openings 42 into the annular passage formed between the collar 40 and valve 39. The air will then pass through the openings 39^a and 80 39^b and openings 34^a and 34^b into the annular passage formed between the valve 34 and collar 32 and is finally permitted to enter the vapor duct through the radially positioned inlet openings 38. The volume of air 85 admitted is, however, controlled, first of all, by means of the valve 39 which is manually operated through a lever connection 43. For instance, if the engine to which the carbureter is connected is running at high 90 speed it must be assumed that the throttle valve 29 is completely open. The air openings in the valves 39 and 34 should then completely register with each other to admit the largest volume of air possible. If 95 it is desired to slow down by means of the throttle, it is only necessary to swing the throttle by means of the crank arm 30. It is also necessary to decrease the proportion of auxiliary air admitted by decreasing the 100 inlet openings through the valves 39 and 34. This is automatically accomplished in the present instance, as valve 34 is directly connected with the throttle valve through means of the gear segment 37 and gear teeth 35. 105 The closing of the throttle valve 29 will thus be followed with a similar or proportional closing of the lower auxiliary air valve 34, as this is turned with relation to the valve 39. This movement is sufficient to bring the 110 openings 34^a and 34^b more or less out of register with the openings 39^a and 39^b and they may be so positioned that the complete closure of the throttle valve will insure a 115 complete closure of the auxiliary air valve 115 connections; this degree of closure being, however, regulated by the valve 39 which is manually operated through the lever 43 to increase the proportional area through the auxiliary air valve for different speeds and 120 altitudes.

An auxiliary air valve constructed as here shown may also be used to a great advantage as a brake, when coasting down hills; as the throttle valve can be completely 125 closed and the valve 39 moved into position where it will register with the openings in the valve 34. The air can thus be drawn in through the openings formed and will consequently enter the cylinders through the 130

inlet valves in the usual manner. The area of the opening through the auxiliary valve will regulate the speed with which the engine can run when going down hill and 5 will consequently act as a brake.

The structure of the spray nozzle is very simple and, practically speaking, forms a multiple jet nozzle by which the spray may be directed over a large area of the exhaust 10 pipe 2. The widely distributed spray thus produced, together with the screen 28 and ribbed heating surface presented by the exhaust pipe 2, forms a means for producing a perfectly vaporized mixture to which auxiliary air may be admitted in the proper 15 proportion through the openings 38.

The float chamber and spray nozzle are made as one unit and are secured to the carbureter casing by screws 50 and 51. The 20 large vapor passage or carbureting chamber formed exterior of the exhaust pipe makes it impossible to choke the carbureter with carbon formations formed interior thereof.

A carbureter constructed as here shown 25 is simple and compact in construction and does not take any more space than the usual form of carbureters now in use. The use of the exhaust heat, together with the novel 30 type of spray nozzle provided, greatly increases the vaporizing efficiency of the carbureter with a consequent reduction in fuel consumption per horse power.

The materials and finish of the several 35 parts of the carbureter are such as the experience and judgment of the manufacturer may dictate.

I wish it understood that various changes in form, proportions and minor details of 40 construction may be resorted to within the scope of the appended claims, and that I do not wish to limit myself to the specific design and construction here shown.

Having thus described my invention, what I claim is—

45 1. The combination in a carbureter, of a heating chamber having an inlet and an outlet, a heating unit in the chamber in the path of the fluid entering through the inlet, said inlet arranged in the form of an elongated slot to permit of the distribution

of the entering fluid over a wide area of heating surface, and means for increasing or decreasing the area of the elongated slot.

50 2. In a carbureter, the combination of a casing having a carbureting chamber therein, a conduit formed in the casing passing through the carbureting chamber through which exhaust gases may be directed to heat the carbureting chamber, a spray nozzle mounted in the casing below the carbureting chamber and the exhaust heated conduit, a pair of wing valves pivotally mounted in the casing above the spray nozzle to direct the incoming air and spray directly against the heated conduit and around same, and

means for turning the wing valves in unison to increase or decrease the outlet area between same.

3. In a carbureter, the combination of a casing having a carbureting chamber therein, an exhaust pipe extending through said carbureting chamber, a plurality of annularly projecting ribs formed on the exterior of said pipe, a spray nozzle mounted in the casing below the carbureting chamber, and a valve for directing the spray and incoming air against the surface of the exhaust pipe. 70

4. A multiple jet spray nozzle for carbureters, consisting of a nozzle casing having an oblong slot formed therein, a valve interior of said casing, a plurality of discharge openings in said valve adapted to register with the oblong slot in the nozzle, means for conveying oil to the discharge openings in the valve, and means for turning the valve to bring said openings into and out of register with the oblong slot. 80

5. A multiple jet spray nozzle for carbureters, consisting of a nozzle casing having an oblong slot formed therein, a valve interior of said casing having an oblong chamber formed on one side, means for conveying oil to said chamber, a plurality of spray openings formed in the valve communicating with said chamber and adapted to register with the oblong slot in the nozzle casing, and means for turning the valve to bring the spray openings into and out of register with the oblong slot in the nozzle casing. 90

6. A multiple jet spray nozzle for carbureters, consisting of a nozzle casing having an oblong slot formed therein, a valve interior of said casing, a plurality of discharge openings in said valve adapted to register with the oblong slot in the nozzle, means for conveying oil to the discharge openings in the valve, means for turning the valve to bring said openings into and out of register with the oblong slot, a pair 105 of wing valves mounted parallel with the nozzle casing, one on each side, and means for raising or lowering said valves in unison with relation to the oblong slot in the nozzle casing. 110

7. A carbureter comprising a casing having a carbureting chamber formed therein, a rectangular shaped extension on the lower end of said casing forming the inlet to the carbureting chamber, a spray nozzle mounted lengthwise in said extension having a discharge slot formed therein of a length approximate to the length of the inlet opening, a valve interior of said spray nozzle having a plurality of spray openings 120 formed therein adapted to register with the discharge slot in the nozzle, means for turning the valve to bring the spray openings into and out of register with the discharge slot, and means for conveying and distribut- 125

- ing fuel oil to the spray openings in the valve.
8. A carbureter comprising a casing having a carbureting chamber formed therein, a rectangular shaped extension on the lower end of said casing forming the inlet to the carbureting chamber, a spray nozzle mounted lengthwise in said extension having a discharge slot formed therein of a length approximate to the length of the inlet opening, a valve interior of said spray nozzle having a plurality of spray openings formed therein adapted to register with the discharge slot in the nozzle, means for turning the valve to bring the spray openings into and out of register with the discharge slot, means for conveying and distributing fuel oil to the spray openings in the valve, wing valves pivotally mounted in the rectangular shaped inlet extension, one on each side of the spray nozzle, and means for raising or lowering said valves in unison with relation to the discharge opening in the nozzle.
9. A carbureter comprising a casing having a carbureting chamber formed therein, a rectangular shaped extension on the lower end of said casing forming the inlet to the carbureting chamber, a spray nozzle mounted lengthwise in said extension having a discharge slot formed therein of a length approximate to the length of the inlet opening, a valve interior of said spray nozzle having a plurality of spray openings formed therein adapted to register with the discharge slot in the nozzle, means for turning the valve to bring the spray openings into and out of register with the discharge slot, means for conveying and distributing fuel oil to the spray openings in the valve, wing valves pivotally mounted in the rectangular shaped inlet extension, one on each side of the spray nozzle, and means for raising or lowering said valves in unison with relation to the discharge opening in the nozzle, said means comprising crank arms, one secured on each wing valve, an extension on the outer end of each crank arm, a slotted bar into which said extensions project, and means for raising or lowering said bar.
10. A carbureter comprising a casing having a carbureting chamber formed therein and an air inlet and an outlet opening, an exhaust pipe extending through said carbureting chamber, a spray nozzle mounted in the casing between the exhaust pipe and the inlet opening, said spray nozzle extending across the casing in alignment with the exhaust pipe and having a long ribbon-like slot formed therein also positioned in alignment with the exhaust pipe, a valve interior of the nozzle having a plurality of discharge openings formed therein adapted to register with the slot in the nozzle, and means for delivering a hydrocarbon fuel to the valve.
11. A carbureter comprising a casing having a carbureting chamber formed therein and an air inlet and an outlet opening, an exhaust pipe extending through said carbureting chamber, a spray nozzle mounted in the casing between the exhaust pipe and the inlet opening, said spray nozzle extending across the casing in alignment with the exhaust pipe and having a long ribbon-like slot formed therein also positioned in alignment with the exhaust pipe, a valve interior of the nozzle having a plurality of discharge openings formed therein adapted to register with the slot in the nozzle, means for delivering a hydrocarbon fuel to the valve, and means for turning the valve to bring the valve openings into and out of register with the slot in the nozzle.
12. A carbureter comprising a casing having a carbureting chamber formed therein and an air inlet and an outlet opening, an exhaust pipe extending through said carbureting chamber, a spray nozzle mounted in the casing between the exhaust pipe and the inlet opening, said spray nozzle extending across the casing in alignment with the exhaust pipe and having a long ribbon-like slot formed therein also positioned in alignment with the exhaust pipe, a valve interior of the nozzle having a plurality of discharge openings formed therein adapted to register with the slot in the nozzle, means for delivering a hydrocarbon fuel to the valve, means for turning the valve to bring the valve openings into and out of register with the slot in the nozzle, a pair of wing valves journaled in the casing, one on each side of the spray nozzle slot, and means for turning said wing valves in unison to increase or decrease the space between the ends of the valves and the spray nozzle.
13. A carbureter comprising a casing having a carbureting chamber formed therein and an air inlet and an outlet opening, an exhaust pipe extending through said carbureting chamber, a spray nozzle mounted in the casing between the exhaust pipe and the inlet opening, said spray nozzle extending across the casing in alignment with the exhaust pipe and having a long ribbon-like slot formed therein also positioned in alignment with the exhaust pipe, a valve interior of the nozzle having a plurality of discharge openings formed therein adapted to register with the slot in the nozzle, means for delivering a hydrocarbon fuel to the valve, means for turning the valve to bring the valve openings into and out of register with the slot in the nozzle, a pair of wing valves journaled in the casing, one on each side of the spray nozzle slot, means for turning said wing valves in unison to increase or decrease

the space between the ends of the valves and the spray nozzle, said means comprising crank arms, one secured on each wing valve, an extension on the other end of each crank 6 arm, a slotted bar into which said extensions project, and means for raising or lowering said bar.

In testimony whereof I have hereunto set my hand in the presence of two subscribing witnesses.
